GUSTAVE M. NELL, OF DETROIT, MICHIGAN, ASSIGNOR TO CHICAGO PNEUMATIC TOOL COMPANY, OF NEW YORK, N. Y., A CORPORATION OF NEW JERSEY

STOPING DRILL

Application filed April 6, 1929. Serial No. 353,209.

This invention relates to apparatus for rock drilling. More particularly it concerns feeding means for percussive motors, such as are commonly used on stoping drills.

5 One object of the invention is to provide a feeding device for self-rotating stopers which will prevent the entire machine from rotating when the drill steel becomes stuck. Another object is to enable the machine to be rotated 10 manually through a sufficient arc to aid in loosening a stuck drill steel. Another object is to improve prior apparatus of this general character. Still further objects will be apparent from the detailed description which 15 follows.

In order to illustrate the invention preferred embodiments thereof are shown in the accompanying drawings, in which:

20 Fig. 1 is a vertical sectional view illustrating a stoping drill in position for operation;

Fig. 2 is an enlarged sectional view of a detail of the feeding device of Fig. 1 showing the connection between the telescoping parts substantially on the line 2—2 of Fig. 3;

25 Fig. 3 is a transverse sectional view substantially on the line 3—3 of Fig. 2;

Fig. 4 is a sectional view showing reversed connections for the telescoping members and a clamping support engaging one of them;

30 Fig. 5 is an elevational view of the support shown in Fig. 4;

Fig. 6 is a fragmentary sectional view through the lower end of a feeding device showing a modification;

35 Fig. 7 is a sectional view substantially on the line 7—7 of Fig. 6;

Fig. 8 is a sectional view similar to Fig. 6 showing still another modification; and

40 Figs. 9 and 10 are fragmentary views at right angles to each other showing the manner of connecting the feeding device to a column.

Fig. 1 illustrates a stoping drill embodying one form of the invention in position for operation. The drill comprises a percussive motor A adapted to impart blows and to rotate a drill steel a supported in the forward end thereof and having a feeding device B for advancing the motor and the steel to the work. While the percussive

motor may have independent means for rotating the drill steel, it is shown as provided with the well-known rifle bar rotation mechanism. Since the percussive motor may be of any suitable or desired type, further description thereof is omitted.

A handle C projects from the machine to be grasped by the operator in directing the machine to the work and in controlling its operation. Handle C is also used to free the machine when the drill steel a becomes stuck in the formation which is being drilled. Since motor A is of the self rotating type, sticking of the steel tends to cause the entire machine to rotate unless suitable means are provided between the motor and the support.

The feeding device shown is of the fluid pressure type and consists of telescoping members 7 and 8, one of which is secured to the drill and the other engages or is engaged by a support. Member 7 is a feed leg cylinder secured to motor A, and member 8 a piston slidable within cylinder 7. The feeding device is arranged to prevent rotation of the motor A when the steel a becomes stuck and yet is arranged to permit a limited amount of rotative movement relative to the support so that the operator may utilize handle C to assist in freeing the steel.

Suitable means may be secured to the lower end of piston 8 to engage the support and to resist rotative movement. In the form of the invention shown in Fig. 1 such means take the form of a foot piece 9 having at least two points 10 to engage a supporting surface. Alternatively or additionally, a hole 11 in the foot piece may be utilized to effect a secure anchorage or to resist movement by inserting a bar therethrough for engagement with a wall or a stone. By preference foot piece 9 has a tongue 12 which extends into a recess or slot in the end of piston 8 and is secured therein by a pivot pin 13.

The means permitting free longitudinal movement of the piston 8 in cylinder 7, but permitting only limited rotative movement of cylinder 7 and motor A relative to foot piece 9, will now be described. Piston 8 has one or more grooves 14 which receives with a

sliding fit corresponding splines or ribs 15 on an annular key 16 rotatively supported in a counterbore in the outer end of cylinder 7. The rotative movement of key 16 is limited by stops or lugs 17 on the latter which engage cooperating stops or lugs 18 on a nut 19 which is threaded into or otherwise secured to cylinder 7. A bushing 20 may be provided at the inner end of the counterbore in the feed cylinder to provide a bearing for key 16. Bushing 20 and nut 19 are in spaced relation, as shown, to allow free rotative movement of key 16 through the arc indicated by the curved double pointed arrows in Fig. 3.

Referring now to Fig. 1 and assuming that drill steel *a* is stuck in the hole and that the rotation train is so arranged that the drill steel rotates in a counter clock-wise direction as indicated by the arrow, the sticking of the steel causes the rest of the machine, as a result of reaction, to turn in a clock-wise direction. As feed cylinder 7 and nut 19 are fastened together, they will rotate with the machine until stops 17 and 18 come in contact, as shown in Fig. 3. Stops 17 on key 16 prevent further rotation of the machine by reason of the splined connection 14, 15 with piston 8 and the engagement of foot piece 9 with the wood, rock, or other supporting surface *x*. To loosen the steel the operator now grips handle C and by pulling the same toward himself forcibly turns the drill steel in the hole through the arc indicated by the arrows in Fig. 3. Upon releasing the pull on handle C the machine is again free to rotate in a clock-wise direction until stops 17 and 18 again engage. This is repeated until the steel is freed.

In Fig. 4 there is a reversal of the connections of the telescoping members of the feeding device but otherwise the elements and the functioning of the same are identical with those previously described. Piston 8' is secured to drill A while 7' carries foot piece 9. A base member E (Figs. 4 and 5) having clamping jaws *e*, *e'* encircling cylinder 7' and held in tight engagement with the same by a bolt *e''* serves as the support in this instance and permits the drill to be mounted on a column in the socket for a shell mounting.

In the modifications shown in Figs. 6 to 8 inclusive, the rotation of the machine relative to the stationary foot piece is provided between the foot piece and the feed device rather than within the feed device itself, as in the form previously described. In Figs. 6 and 7 the feeding piston 8a has a splined connection with a nut 19a secured in the outer end of feed cylinder 7a so that axial movement of the telescoping parts is provided for but relative rotation is positively prevented. Piston 8a is provided with an extension 21 threaded thereinto or otherwise fixedly secured to the piston and may have a

spur 22 for engaging a supporting surface *x*. An enlarged portion of the extension 21 has a bore 23 therethrough transverse to the axis of the machine and this bore is flared or fan shaped divergently from its center, as shown in Fig. 7. Through bore 23 extends a foot piece 24 in the form of a rod having bent ends 24a sharpened to provide spurs which engage the support *x* at spaced points. Foot piece or rod 24 accordingly has a pivotal connection with piston extension 21 and the fanning or flaring of the bore 23 permits a limited amount of rotative movement of the entire machine on foot piece 24 to permit the operator to rock the machine on its axis to release a stuck steel.

The modification shown in Fig. 8 is similar to that shown in Figs. 4 and 5 in that piston 8b has a splined connection with a nut 19b in cylinder 7b and has an extension 25 threaded into the end of piston 8b. Extension 25 is annular in shape and has a flange 25a which serves to clamp to the piston a spurred foot piece 26 provided with a central bore 26a through which extension 25 extends. Thus foot piece 26 is arranged for pivotal movement in a rotary sense upon piston 8b as an axis but by reason of its spurs it engages the supporting surface *x* in a fixed position. To limit the amount of permissive rotative movement of the machine relative to foot piece 26, extension 25 has a boss or projection 25b with a transverse bore through which extends a stop bar 27 of sufficient length to engage one or more of the spurred arms of foot piece 26.

Figs. 9 and 10 illustrate the use of a column or column bar F as a support for the drilling apparatus by providing a clamping sleeve having bolts *g* one of which extends through a bore 11a in a foot piece or extension 9a upon one of the telescoping members of the feeding device.

While the invention has been herein described in what are now considered to be preferred forms, it is to be understood that the invention is not limited to the specific details thereof but covers all changes, modifications, and adaptations within the scope of the appended claims.

I claim as my invention:

1. In combination, a rock drill having a percussive motor, telescoping members forming a pressure feeding device comprising a cylinder and a piston slidably therewithin, one of said members being secured to said motor, means on said other member for engaging a support and for resisting rotative movement, said piston having grooves, said cylinder having a counterbore adjacent its free end, an annular key in said counterbore having splines for slidably engaging the grooves in said piston, a nut for holding said key in place and permitting limited rotative movement of the same, said key having a

radial extension and said nut an axial extension, said extensions forming stops for direct engagement.

2. In combination, a rock drill having a percussive motor, telescoping members forming a pressure feeding device comprising a cylinder and a piston slideable therewithin, one of said members being secured to said motor, means on said other member for engaging a support and for resisting rotative movement, said cylinder having a counterbore adjacent its free end, a bushing in said counterbore, an annular key rotatably supported in said bushing, interengaging means on said key and said piston permitting relative axial movement only, and a nut for retaining said key and bushing in place having a fixed stop projection for direct engagement by said key positively to limit the rotation of the latter.

3. In combination, a rock drill having a percussive motor, telescoping members forming a pressure feeding device comprising a cylinder and a piston slideable therewithin, one of said members being secured to said motor, means on said other member for engaging a support and for resisting rotative movement, said piston having grooves, said cylinder having a counterbore adjacent its free end, a bushing in said counterbore, an annular key rotatably supported in said bushing and having splines slidably engaging the grooves in said piston, a nut for retaining said key and bushing in place, and lugs on said key and nut arranged for direct engagement positively to limit the rotation of the former.

Signed by me at Detroit, in the county of Wayne and State of Michigan, this 2nd day of April, 1929.

GUSTAVE M. NELL.
